POT TYPE BURNER WITH ADMISSION OF
AIR AT TWO LEVELSBruce Hayter, Santa Fe, N. Mex., assignor to Oil
Devices, Santa Fe, N. Mex., a limited partner-
ship of Illinois

Application November 14, 1941, Serial No. 419,103

2 Claims. (Cl. 158—91)

This invention relates to an improvement in liquid hydrocarbon burners and has for a particular purpose the provision of an improved pot type burner having a maximum turndown.

Another purpose is the provision of such a burner in which a baffle or pilot ring is employed in order to permit a minimum turndown when minimum heat or no heat is desired.

Another purpose is the provision of a simplified pot type burner in which the air is admitted to the pot at a minimum of separate levels.

Another purpose is the provision of a pot type burner in which the combustion at all stages is substantially free from smoke or carbon deposit.

Other purposes will appear from time to time in the course of the specification.

The invention is illustrated more or less diagrammatically in the accompanying drawing wherein:

Fig. 1 is a vertical axial section; and

Fig. 2 is a section on the line 2—2 of Fig. 1.

Like parts are indicated by like symbols throughout the specification and drawing.

Referring to the drawing, 1 generally indicates an outside housing, herein shown as in the form of a drum or cylinder supported on any suitable means, such as the supporting ring or base 2, with feet or supports 3 adapted to elevate the drum 1 above the floor or supporting surface so that air may penetrate therebeneath. 4 is any suitable bottom member having a central aperture 5 for the admission of air to the space within the lower portion of the drum 1.

6 is a burner pot, having a slightly concave bottom 7 and a liquid fuel inlet pipe 8 from any suitable source of liquid fuel not herein shown. It will be understood that any suitable valve means not herein shown, which may be automatic or manual, may be employed for varying the supply or volume of flow of the liquid fuel to the pot.

The pot is provided with an upwardly and outwardly extending flange 10, which may rest on any suitable supporting flange 11, which is effective also to close the space between the pot and the drum 1 so that air cannot pass from the space between the pot 6 and the drum 1 except by passing through the apertures in the pot itself. I illustrate two rows of air inlet apertures, a lower row 12 and an upper row 14. Preferably the apertures of the upper row 14 are upwardly and inwardly tilted in order to project air jets upwardly and inwardly into the space within the pot 6. 15 is any suitable baffle or pilot ring, which may rest for example on inwardly

extending supports or pins 16. Preferably I provide a clearance, as at 17, between the periphery of the ring 15 and the opposite wall of the pot.

20 is any suitable fire ring adapted to close 5 the top of the pot except for the axial outlet or opening 21. 22 is any suitable wall for the combustion chamber proper. It will be understood that any suitable flue means may be employed for maintaining proper draft conditions and for carrying off the products of combustion from the combustion chamber 22. It will be understood also that, if the invention is applied to a hot water heater, it may be desirable to employ a central wall or flue, indicated in dotted line as 15 at 23, which may be positioned between the flanges 24 and 25 upwardly extending from the fire ring 20. In that event any suitable packing 26 may be employed.

In proportioning the holes 12 and 14, it is found 20 desirable to have a substantially larger number of holes at the upper level. The holes are so proportioned in Fig. 1 as to provide forty holes at the lower level and one hundred holes at the upper level, the lower level holes being of slightly 25 greater diameter.

It will be realized that, whereas a practical 30 and operative device is described and illustrated, nevertheless many changes may be made in the size, shape, number and disposition of parts, without departing from the spirit of the invention. It is therefore wished that the description and drawing be taken as in a broad sense 35 illustrative or diagrammatic, rather than as a limitation to the precise showing. The use and operation of the invention are as follows:

It has been customary in the past in pot type 40 burners to employ a plurality of air inlet apertures in the wall of the pot, located at a plurality of different levels. In order to simplify the structure and to improve its operation, I find it 45 desirable to concentrate the apertures at two levels. Stated otherwise, this involves delivering air to the pot at only two levels, one above the pilot ring and the other below.

It will be understood that, when the burner 50 is operated at the lower or pilot stage, the apertures 12 provide enough air for the combustion of all of the liquid fuel supplied along the inlet 8, this combustion taking place at or slightly 55 above the level of the apertures 12, or, in practice, at the level of the central aperture 15a of the pilot ring where the primary mixture formed below the pilot ring is mixed with the secondary air present in the upper portion of the pot. When the flow of liquid hydrocarbon is increased, the

flame level rises until it is above the apertures 14, or, in practice, at the aperture 21 of the flame ring 20.

What is claimed is:

1. In a pot type burner for liquid fuel, a pot having a bottom and a generally cylindrical side wall, a centrally apertured flame ring partially closing the open top of the pot, said side wall having a single row of secondary air inlet apertures spaced slightly below said flame ring, and having a single row of primary air inlet apertures located generally midway between top and bottom of the pot, a liquid fuel inlet pipe extending from a source of fuel supply to the pot at a level below said row of primary air inlet apertures, and a single centrally apertured pilot baffle positioned above the row of primary air inlet apertures and below the row of secondary air inlet apertures, the total cross sectional area of the secondary air inlet apertures substantially exceeding the total cross sectional area of the primary air inlet apertures. 20

2. In a pot type burner for liquid fuels, a pot having a bottom and a generally cylindrical side wall, a centrally apertured flame ring partially closing the open top of the pot, said side wall having a single row of secondary air inlet apertures spaced slightly below said flame ring, and having a plurality of primary air inlet apertures located substantially in the lower half of the pot wall, a single centrally apertured pilot baffle positioned above all the primary air inlet apertures and below the row of secondary air inlet apertures, and substantially closer to the primary than to the secondary air inlet apertures, the total cross sectional area of the secondary air inlet apertures exceeding the total cross sectional area of the primary air inlet apertures, and means for delivering liquid fuel to the space between the pilot baffle and the pot bottom. 15

BRUCE HAYTER.
